LUGGAGE CASE

Anthony N. D'Elia, New York, and Edward M. Stolarz,
Yorktown Heights, N.Y., assignors to Reliable Luggage,
Inc., West Pittsburgh, Pa., a corporation of Pennsylvania

Filed Feb. 12, 1968, Ser. No. 10,542

Term of patent 14 years

Int. Cl. D3—01

U.S. Cl. D87—5

Fig. 1.

Fig. 2.

Fig. 3.

Fig. 4.

FIG. 1 is a perspective view of a luggage case showing our new design;

FIG. 2 is an elevation thereof on a reduced scale, the side opposite being identical thereto;

FIG. 3 is an end elevation thereof opposite that shown in FIG. 1; and

FIG. 4 is a top plan view.

The essential features of the design reside in the full line portions, and particularly in the concave portions of the shell edges.

We claim:

The ornamental design for a luggage case, as shown and described.
